COMBINED LETTER OPENER AND KNIFE OR
SIMILAR ARTICLELeo F. Wildgen, Minneapolis, Minn., assignor to Arthur
Salm Inc., Chicago, Ill., a corporation of IllinoisContinuation of design application Ser. No. 2,084, May
2, 1966. This application Dec. 11, 1967, Ser. No. 9,746

Term of patent 14 years

(Cl. D74—10)

FIG. 1 is a top plan view of a combined letter opener and knife or similar article incorporating my new design;

FIG. 2 is a side view thereof;

FIG. 3 is a handle end view thereof with the broken lines of FIGS. 1 and 2 omitted for convenience of illustration;

FIG. 4 is a blade end view thereof; and

FIG. 5 is a fragmentary plan view of the handle end thereof showing the various blade tools in open position.

The bottom and the side opposite to that disclosed in FIG. 2 are substantially similar in appearance to the views shown respectively by FIGS. 1 and 2.

The characteristic features of my design shown in solid lines reside in the unitary appearance of the handle and letter opener blade member wherein the narrower, thicker handle is offset from the letter opener blade by means of a chevron or fishtail configuration, all as shown, the broken line showing of the various blade tools in FIGS. 1, 2 and 5 being for illustrative purposes only.

This application is a continuation of my application Ser. No. D. 2,084 filed May 2, 1966, and now abandoned.

I claim:

The ornamental design for a combined letter opener and knife or similar article, substantially as shown and described.
